UNITED STATES PATENT OFFICE.

ALBERT W. BACHMANN, OF LAPORTE, INDIANA.

WATER-HEATER FOR FURNACES AND THE LIKE.

1,351,606.

Specification of Letters Patent. Patented Aug. 31, 1920.

Application filed August 6, 1917. Serial No. 184,673.

To all whom it may concern:

Be it known that I, ALBERT W. BACHMANN, a citizen of the United States residing at Laporte, county of Laporte, State of Indiana, have invented certain new and useful Improvements in Water-Heaters for Furnaces and the like, of which the following is a specification.

This invention relates to improvements in water heaters for furnaces and the like.

My improved water heater or boiler is designed to be suspended within the firepot of a hot air furnace or a hot water or steam boiler, for supplying hot water to hot water systems such as are used for heating or for domestic purposes.

The main objects of this invention are:

First, to provide a device of the type described which may be supported in a firepot in position so that fuel may be heaped around and upon the same and the side walls of which are so constructed as to provide a plurality of flues causing effective combustion around the heater and also tending to direct the heat currents thereto and also to provide a very large surface for the conduction of heat.

Second, to provide an improved water heater adapted to be disposed in the firepot of a furnace, which is of small dimensions and at the same time of very large capacity and very efficient.

Third, to provide an improved heater of this type which is adapted to be mounted in the most convenient position according to the particular furnace or firepot in which it is to be installed.

Further objects, and objects relating to structural details, will definitely appear from the detailed description to follow.

I accomplish the objects of my invention by the devices and means described in the following specification. The invention is clearly defined and pointed out in the claim.

A structure which is a preferred embodiment of my invention is clearly illustrated in the accompanying drawing, forming a part of this specification, in which:

Figure I is a detail vertical section through a hot air furnace structure embodying the features of my invention, parts other than my improved heater being shown mainly in conventional form.

Fig. II is a detail horizontal section on a line corresponding to line 2—2 of Fig. I.

Fig. III is a detail vertical section of my improved heater arranged in the firepot of a steam or hot water heating boiler.

Fig. IV is a detail vertical section of a hot air furnace similar to that shown in Fig. I with my improved heater disposed in a horizontal position.

Fig. V is a detail vertical section of a hot air furnace showing another method of connection of the circulating pipes.

Fig. VI is a longitudinal section of my improved heater on a line corresponding to line 6—6 of Fig. VII.

Fig. VII is a transverse section on a line corresponding to line 7—7 of Fig. VI.

Fig. VIII is a perspective view of my improved heater.

In the drawing similar reference characters refer to similar parts throughout the several views, and the sectional views are taken looking in the direction of the little arrows at the ends of the section lines.

Referring to the drawing, the reference character 1 indicates my improved water heater generally. The side walls of my improved heater are formed of a plurality of hollow longitudinal ribs 2 of uniform and substantially rectangular cross section. These ribs are disposed radially so that the edges of adjacent walls are joined at 3, forming V-shaped spaces 4 between them which provide flues for the hot gases. One of the ribs, as 5, is enlarged, being of materially greater width and diameter than the other ribs and has provision for pipe connections. The enlarged rib 5 has a pair of threaded openings 6 located near the top and bottom and adapted to receive the circulating pipes. One end of the heater is provided with an oblong-shaped boss 7 extended onto the end of the enlargement 5. This boss 7 is tapped at 8 to receive the pipe connections. One of the openings 8 is located substantially in the longitudinal center of the series of radial ribs, and the other opening leads into the end of the enlarged rib 5, being spaced from the first-mentioned opening and the radial ribs. Except for this boss 7 the end walls are flat.

The enlarged rib 5 has a flat thickened outer wall substantially oblong shaped in outline in which the spaced threaded openings 6 are provided, and said rib 5 is offset from the radial ribs 2, the latter being arranged in a circular series of which the inner opening 8 forms the center.

In the preferred installation, as shown in Figs. I, II and III, I dispose the heater vertically and in a position below the fire line of the firepot 9, so that the fuel introduced through the door 10 may be heaped about and upon the heater. The ribs 2 run vertically and being relatively close together provide a series of flue spaces 4, which cannot become obstructed with coal and cause a circulation about the heater insuring combustion of the fuel heaped against the same and also directing the hot gases toward and against the walls of the heater.

The circulation pipes 11 are connected to the end connections, the side connections being closed by plugs 13, as shown in Fig. I, or one pipe may be connected to one end connection and the other to one side connection, as shown in Fig. III.

In the embodiment shown in Fig. I the pipes are arranged through the door frame and along the fire door passage of the furnace, their outer ends being connected to the tank 12.

In the embodiment shown in Fig. III, the circulation pipes are arranged through the wall of the firepot.

In Figs. IV and V the heater is shown arranged on its side and, while it is effective as a heater arranged in this relation, it is particularly desirable when arranged as shown in Figs. I, II and III.

The adaptations illustrated indicate that my improved heater may be located and connected to meet particular requirements, but is most efficient when located in the firepot below the fire line or so that the fuel may be heaped about the same, as shown in Figs. I, II and III. The special advantage of providing the pipe connections on the extended flat wall of the enlargement 5 and the boss 7 is that it permits the heater to be tapped on the side and on the top, making the heater adaptable to any kind of water connection, and at the same time it eliminates all air pockets within the heater body. The presence of such air pockets would necessarily diminish the water-receiving capacity of the heater.

My improved heater is compact and at the same time of large heating capacity. I have illustrated such adaptations thereof as I be-

lieve will enable those skilled in the art to embody or adapt my improvements as may be desired.

There are, however, three other positions, not shown, which the circulating pipes may assume in applying the heater in place. In other words, there are seven distinct ways in which the heater may be mounted in connection with the cold and hot water pipes, differing in this respect from anything now on the market.

Having thus described my invention, what I claim as new and desire to secure by Letters Patent, is:

In a structure of the class described, a water heater adapted to be arranged in either a vertical or horizontal position within a fire pot, comprising a hollow body formed of a single piece, said body having approximately flat end walls, one of which is formed with a pair of spaced openings for the connection thereto of either pipes or plugs, and side walls formed of a plurality of longitudinal hollow ribs disposed in a circular series to provide narrow flue spaces between the ribs, and another longitudinal hollow rib of greater width and diameter than the other ribs and offset therefrom at one side and having its outer wall provided with a pair of openings for the connection thereto of either pipes or plugs, said openings being located near the top and bottom of the body, the inner one of the two openings in the end wall being located at one end of the body where the plurality of hollow ribs are provided and substantially in the longitudinal center of said ribs, the other of said openings being provided at the end of the rib of greater width and diameter and adjacent to the top opening therein, whereby the water circulating pipes may be connected to the body in a plurality of different ways and air pockets within the heater body are eliminated.

In witness whereof, I have hereunto set my hand and seal in the presence of two witnesses.

ALBERT W. BACHMANN. [L. S.]
